CURTAIN SUPPORTING ARRANGEMENT

Erwin E. Widman, Little Neck, N. Y.

Application November 13, 1933, Serial No. 697,748

10 Claims. (Cl. 156—13)

My invention relates to a supporting arrangement for curtains, drapes or the like.

My invention has particular reference to various novel features and characteristics of a supporting arrangement of the character stated.

Various other objects, advantages and characteristics of my invention will become apparent from the following detailed description.

My invention resides in the supporting arrangement, features, and details of construction of the character hereinafter described and claimed.

For an understanding of my invention and for an illustration of some of the forms thereof, reference is to be had to the accompanying drawing, in which:

Fig. 1 is a perspective view showing curtains and drapes associated with a window;

Fig. 2 is a horizontal sectional view, partly in plan, showing features of my novel supporting arrangement;

Fig. 3 is a vertical sectional view, partly in elevation and is taken on the line 3—3 of Fig. 2 looking in the direction of the arrows;

Fig. 4 is a perspective view of a section of my novel supporting arrangement;

Fig. 5 is a perspective view illustrating a modification of the invention;

Fig. 6 is a horizontal sectional view, partly in plan, illustrating features of the invention as disclosed in Fig. 5; and

Fig. 7 is an elevational view illustrating a detailed feature of the invention.

Referring to the drawing, C represents a suitable curtain supporting arrangement or cornice which is herein shown as comprising a front section 1 and side or end sections 2, 2a disposed in substantially parallel relation with respect to each other and at right angles to said front section 1. In the form of my invention herein shown, although not necessarily, the aforesaid cornice sections are formed from sheet metal and the cornice end sections 2, 2a are soldered, welded or otherwise suitably secured to the cornice front section 1. Obviously, the cornice sections may be of such ornamental configuration as may be suitable or desirable.

In Fig. 2, I have shown spaced members 3, 3a which constitute the vertical side sections of a window or door frame. Disposed at the front of the aforesaid frame are the vertical side members 4, 4a and these are utilized, in a preferred form of the invention, for supporting the aforesaid cornice C.

To this end, and as shown in Figs. 2 and 3, a

pair of spaced members 5 may extend horizontally from the outer, vertical surface 4b of each of the members 4, 4a. When the members 4, 4a are formed from wood, the members 5 may be ordinary headed screws which are only partly threaded into said members 4, 4a so that a part of the screw shanks are exposed, Fig. 2. Since the members 5 extend from the respective surfaces 4b of the vertical members 4, 4a, it will be obvious that said members 5 are disposed substantially parallel with respect to the front faces 4c of the vertical members 4, 4a. In other words, the members 5 are disposed substantially parallel with respect to the plane of the window or door frame.

For securing the cornice C to the members 5, there may be provided a pair of bracket members 6, 6a which are soldered or otherwise suitably secured in vertical relation to the respective cornice end sections 2, 2a. As shown, these bracket members are disposed interiorly of the cornice structure and at the extreme ends of the respective cornice end sections 2, 2a.

The aforesaid bracket members 6, 6a are formed, preferably, from stiff, non-yielding sheet metal and they are generally square or rectangular when viewed in plan, the arrangement being such that, when the cornice is in position at the top of the window frame, one bracket face 6b takes a position close to and parallel with respect to the adjacent frame or wall surface while another bracket face 6c takes a position close to and parallel with respect to the adjacent vertical member surface 4b.

Referring particularly to Fig. 4, the face 6b of each bracket is shown as provided with slots 6d of such configuration that the heads of the respective screws 5 pass readily therethrough, these slots being spaced in correspondence with the spacing of the screws 5 as positioned on the aforesaid vertical members 4 and 4a. The face 6c of each bracket is provided with bayonet slots 6e disposed in alignment with the respective slots 6d and of such dimensions that the shanks of the respective screws 5 pass readily therethrough.

With the headed screws 5 supported by and projecting in opposite directions from the respective members 4, 4a, it will be obvious that the cornice C may be elevated to substantially its proper position and the bracket slots 6d positioned opposite the heads of the respective screws 5. In this connection, it will be understood that the length of the cornice is so chosen that the bracket slots 6d may be thus positioned opposite the heads of the respective screws 5 without sepa-

ration or "springing" of the cornice end sections. Thereupon, the cornice may be moved toward the window frame whereby said bracket slots 6d are moved beyond the respective screw heads, the shanks of said screws entering the bayonet slots 6e and seating in the angular sections thereof when the cornice C is slightly lowered.

It has been demonstrated in practice that a bracket arrangement of the character described is highly advantageous and practical. The brackets when used as described in conjunction with the members 5 support the cornice C in a steady, non-sagging manner even though the weight of the curtains or drapes hanging from said cornice is substantial. Moreover, the cornice may readily and quickly be attached to or detached from the supporting members 5.

Preferably, as shown on the drawing, the bracket faces 6b carry sheets or pads 7 of rubber or other suitable resilient material to thereby prevent marring or scratching of the frame or wall surfaces with which these bracket faces contact.

Disposed interiorly of the cornice C and adjacent the cornice end sections 2, 2a are the respective bars or members 8, 8a provided with upwardly facing rack teeth 8b. These bars may be supported in horizontal position in any suitable manner. For example, metallic brackets 9, 9a may be soldered or welded in each corner of the cornice C, each of these brackets being provided with upwardly extending slots. At the level of these slots, the face 6f of each of the brackets 6, 6a may be provided with a passage. Accordingly, one end of the rack bar 8 may be passed into the passage in the face 6f of the bracket 6 and the other end of said rack bar 8 may be seated in the slot of the bracket 9. In this manner, the rack bar 8 may be firmly seated horizontally at the interior of the cornice end section 2 and, obviously, in a similar manner, the rack bar 8a may be seated adjacent the interior surface of the cornice end section 2a.

The rack bars 8, 8a are adapted to support, transversely with respect thereto, one or more rods 10 which are horizontally disposed within the cornice C. These rods 10 may be of any suitable character although, preferably, they are formed from metallic material such, for example, as sheet metal. In a preferred form of the invention and as shown in Fig. 7, opposite ends of each bar 10 is of inverted U configuration, the U-legs 10a being formed from resilient sheet metal. When a rod 10 is to be positioned on the rack bars 8, 8a, these U-legs 10a are moved toward each other and then moved downwardly so as to be positioned, respectively, between adjacent pairs of rack teeth. When thus positioned, the inherent resiliency of said U-legs 10a causes the rod 10 to be positively retained in its intended position.

Any desired number of the rods 10 may be positioned in such suitable spaced relation on the rack bars 8, 8a as may be desirable. These rods carry the various curtains or drapes K, Figs. 1 and 2, which are positioned in front of or at the sides of the window, door or the like.

As well shown in Figs. 2, 3 and 4, an elongated bracket 11 is soldered or welded to the interior surface of the cornice member 1. As illustrated, the bracket 11 comprises a section which projects laterally from the cornice member 1 and this lateral section is provided with a plurality of closely spaced holes or perforations 11a. A valance V, at its upper edge, carries a plurality of spaced hooks 13 and, by proper selection of the holes 11a

into which the hooks 13 are to be inserted, the valance V may be hung in an ornamental manner as well shown in Fig. 1. By providing a relatively large number of the perforations 11a compared to the number of the hooks 13, the position taken by the valance may be adjusted within close limits so as to obtain a highly ornamental effect.

In the form of the invention above described, the members 5 for supporting the cornice C are disposed substantially parallel with respect to the plane of the window or door opening. This is a preferred arrangement but it is to be understood that my invention is not to be limited to this particular arrangement.

Thus, as indicated in Figs. 5 and 6, a pair of spaced screws 14 may be disposed at each side of the window or door opening, the screws 14 of each pair being disposed in vertical alignment and all of the screws being disposed substantially at right angles with respect to the plane of the window or door opening.

For association with the pair of screws 14 at the right, Fig. 6, the face 6c of the bracket 6a may be provided with horizontal slots 6g and the faces 6b and 6f of said bracket 6a may be provided with bayonet slots 6h, Fig. 5.

The bracket 6, which is to be associated with the pair of screws 14 at the left, Fig. 6, has its face 6i provided with horizontal slots 6j, these slots corresponding with the above described slots 6g. Further, as indicated, the adjacent surface of the cornice end section 2 is provided with horizontal slots 2b which are aligned with the respective slots 6j. The faces 6b and 6f of the bracket 6 are provided with bayonet slots 6k, the latter corresponding with the aforesaid bayonet slots 6h.

In order to associate the bracketed cornice of Fig. 6 with the respective pairs of screws 14, the cornice is elevated to approximately its intended position with the horizontal slots 6g directly to the right of the respective screws 14 of the right hand pair and with the horizontal slots 2b, 6j directly to the right of the respective screws 14 of the left hand pair. Thereupon, the cornice assembly is moved to the left, Fig. 6, the screws 14 passing through the aforesaid horizontal slots and coming to rest, after slight downward movement of the cornice assembly, in the pockets of the respective bayonet slots 6h and 6k. In this manner, the cornice assembly of Fig. 6 is firmly and securely anchored in its intended position.

With the form of my invention illustrated in Figs. 1-4, it shall be understood that the pairs of screws 5 need not necessarily be supported by members such as the respective vertical members 4, 4a. As well, with the form of the invention just noted, these screws 5, or equivalent, may be supported in any suitable manner so long as they are disposed substantially parallel with respect to the plane of the window or door opening. Similarly, with respect to the form of the invention of Figs. 5 and 6, the pairs of screws 14, or equivalent, may be supported by any suitable members or structure so long as they are disposed substantially perpendicular to the plane of the window or door opening.

A further feature of my invention is shown in Fig. 6. As illustrated, any suitable lamp L1 such, for example, as a neon lamp is supported by an adjacent wall or frame surface, or in or by the cornice C. As indicated, the lamp L1 may be supported by one or more brackets 20 which are carried by the respective cornice end sections.

It will be understood that the arrangement de-

scribed is of the indirect lighting type in that the cornice serves as a shield preventing casual observation of the lamp L, although the rays therefrom pass downwardly to effect illumination of one or more of the curtains K. A reflector may be used to direct the rays downwardly in the manner described or upwardly or both downwardly and upwardly at the same time. One or more colored glass sections or the like may be interposed in the path of the light beam or beams to obtain such color effects as may be desired.

While the invention has been described with respect to certain particular preferred examples which give satisfactory results, it will be understood by those skilled in the art after understanding the invention, that various changes and modifications may be made without departing from the spirit and scope of the invention and it is intended therefore in the appended claims to cover all such changes and modifications.

What is claimed as new and desired to be secured by Letters Patent is:

1. The combination with a cornice comprising a front section having end sections extending at right angles with respect thereto, of vertically disposed brackets terminally secured to the respective end sections, each of said brackets having faces meeting to form an angle, said faces being provided, respectively, with slots which merge into each other to form a passage for a shank-like supporting member.

2. The combination with a cornice comprising a front section having end sections extending at right angles with respect thereto, of vertically disposed brackets terminally secured to the respective end sections, each of said brackets having faces meeting to form an angle, said faces being provided, respectively, with slots which merge into each other to form a passage for a shank-like supporting member, the slot in one only of said faces being of bayonet character.

3. The combination with a pair of vertically aligned, spaced supporting members disposed adjacent each side of a window or door opening and disposed in or parallel with respect to the plane thereof, of a pair of brackets each provided with a pair of slots, each slot being engageable with one of said supporting members, upon movement of said brackets at right angles toward the plane of said window or door opening, and a cornice secured to said brackets.

4. The combination with a cornice having parallel end sections joined by a transverse front section, of a bar disposed adjacent each cornice end section, means for securing the bars to said cornice, said bars having closely spaced, upwardly facing rack teeth, and a curtain-supporting rod carried by said bars and being retained in a selected position by engagement thereof with said rack teeth.

5. The combination with a cornice having parallel end sections joined by a transverse front section, of a bar disposed adjacent each cornice end section, means for securing the bars to said cornice, said bars having closely spaced, upwardly facing rack teeth, and a curtain-supporting rod carried by said bars and being retained in a selected position by engagement thereof with said rack teeth, each end of said curtain-supporting rod being formed from spaced members of

inverted U configuration, said U members entering between adjacent rack teeth and resiliently engaging surfaces thereof.

6. The combination with a cornice having parallel end sections joined by a transverse front section, of a bracket terminally secured to one of said end sections, a bracket secured adjacent the juncture of said last named end section with said front section, and a bar carried by said brackets, said bar being adapted to support one end of a curtain-supporting rod.

7. The combination with a cornice comprising a front section having end sections extending at right angles with respect thereto, of a bracket for supporting a valance, means for securing said bracket to the interior surface of said cornice front section, said bracket being provided with a plurality of closely spaced perforations, said valance being provided with a plurality of hooks spaced substantially further apart than said perforations.

8. The combination with a cornice comprising a front section having end sections extending at right angles with respect thereto, of vertically disposed brackets terminally secured to the respective end sections, each of said brackets having faces meeting to form an angle, said faces being provided, respectively, with slots which merge into each other to form a passage for a shank-like supporting member, a bar disposed adjacent each cornice end section, means for securing the bars to said cornice, said bars having closely spaced, upwardly facing rack teeth, and a curtain-supporting rod carried by said bars and being retained in a selected position by engagement thereof with said rack teeth.

9. The combination with a cornice comprising a front section having end sections extending at right angles with respect thereto, of vertically disposed brackets terminally secured to the respective end sections, each of said brackets having faces meeting to form an angle, said faces being provided, respectively, with slots which merge into each other to form a passage for a shank-like supporting member, a bar disposed adjacent each cornice end section, means for securing the bars to said cornice, said bars having closely spaced, upwardly facing rack teeth, a curtain-supporting rod carried by said bars and being retained in a selected position by engagement thereof with said rack teeth, each end of said curtain-supporting rod being formed from spaced members of inverted U configuration, said U members entering between adjacent rack teeth and resiliently engaging surfaces thereof, and a bracket secured to the interior surface of said cornice front section, said last-mentioned bracket being adapted to support a valance.

10. The combination with a cornice having parallel end sections joined by a transverse front section, of a bar disposed adjacent each cornice end section, means for securing the bars to said cornice in horizontal position, said bars having spaced, upwardly projecting teeth, and a curtain-supporting rod carried by said bars, the ends of said rod engaging and coacting with said teeth to thereby prevent casual movement of said rod with respect to said bars.
